UNITED STATES PATENT OFFICE.

OTHMAR MAYCEN, OF NEW YORK, N. Y.

WASHING MACHINE.

Application filed May 9, 1927. Serial No. 189,952.

This invention relates to washing machines and it particularly relates to a washing machine in which water is used for performing the cleaning process as well as 5 for performing the mechanical work in support of said cleaning process.

The object of the invention is to provide means for washing smooth surfaces, such as are offered by plates, dishes, pans, automobiles, etc., and to remove any grease, food 10 particles or other waste from the same.

It is another object of the invention to provide a washing machine for cleaning dishes and the like articles by a machine 15 which, while furnishing all the power necessary for accomplishing the desired purpose, is of such simple construction that it can be made at a reasonably low price so as to become available to households of moderate 20 income.

It is a further object of the invention to furnish automatic means of light weight to be held in the hand to accomplish the cleaning of dishes in an easy and convenient 25 manner so as to relieve the housewife of much burdensome work and drudgery, especially by avoiding the constant dipping of her hands into the hot soiled water.

According to this invention the washing 30 machine includes a water motor imparting rotary motion to a brush, or wiper or the like means which may be flooded with water during the operation of the same.

With the foregoing and other objects in 35 view, which will be apparent from the following description, reference is had to the accompanying drawings, in which—

Fig. 1 represents a plan view of the machine in slightly smaller size than it is made 40 at present, parts of the shell, covering the movable parts of the machine, and parts of the adjoining handle being removed to give a top view of the said movable parts and a horizontal sectional view of those of the 45 handle.

Fig. 2 is a top view of a lever attached to the handle of the washing machine and operatively connected with a valve;

Fig. 3 is a full view of a bracket for 50 mounting the rotary shaft;

Fig. 4 is the front elevation of the pointed end of the shell surrounding the movable parts.

In the drawings 10 denotes a hollow shell 55 or casing consisting of the cone-shaped front part 11 and the ball-shaped rear part 12.

The wall of the pointed cone 11, of the shell 10, is provided with suitable apertures 13, for instance slots or round holes, for the passage of water and in the center it has a suitable aperture 14 which serves as a journal for the rotary shaft 15 provided therein and which is furthermore operatively arranged in the aperture 16 of a bracket 17 suitably arranged through the center of the ball 12 and perpendicularly to the shaft 15.

At the end of this shaft 15, extending beyond the bracket 17, a gearwheel 18 is secured to the shaft 15 by any means and held in place by a collar 19, or the like. 70 At the front a brush or wiper 20, made of animal or vegetable fiber, or if necessary of metallic thread, for instance of short steel wire, is detachably secured with its holding plate 21 to the front end of the shaft 15. A gearwheel 22 of relatively smaller diameter than that of the wheel 18, is rigidly secured to the basket shaped turbine wheel 23 inside at its center, both wheels forming one whole, which is loosely arranged on the bracket 17. The turbine wheel can be supported in its position in various ways; for instance its hub 25 can be extended downwardly to the wall of the shell 10 so as to rest on the same during 75 its rotation. A plate 24 with a central opening 26 is provided below the turbine which passes through said opening 26 leaving an annular interstice which serves as a 80 passageway for water.

The lower right quarter section of the ball 12 is provided with an inwardly extending sleeve 27 provided with a screw thread so as to be closed by a threaded plug 28, preferably made of hard rubber, 95 engaging the thread of the sleeve 27. A passageway 29 is provided in said plug 28 to serve as an air vent admitting air into the inside of the shell 10. Following the direction of the curvature of the plate 24 and disposed tangentially to the same, a short tubular neck 31 is attached to and 100 communicates with the inside of the shell 10. The neck 31 is provided inside with a screw thread so as to engage the outside thread of a tubular terminal of a chamber 32 communicating with a tube 33 passed through and projecting at both ends from the handle 34. The tube 33 is connected with a rubber hose 35 by which it is connected to a faucet 110 (not shown) supplying hot or cold water as the situation may require. Between the

chamber 32 and the tube 33 an annular channel 36 is interposed at a substantially right angle to said tube and chamber. Inside said channel 36 a spring actuated gate valve 37 is arranged, which is operatively connected by the rod 38, movably arranged in the wall of the chamber 36, with the lever 39; this lever 39 has furthermore a round hole at its other end with which it is slipped over the free rear end of the tube 33. The lever 39 conforms with its shape to that of the handle 34 so that it lays tightly to the same when the machine is held in the hand when used.

15 On the peripheral face 40 of the basket shaped turbine wheel 23 a plurality of wings 41 are arranged in suitable distance from each other. These wings 41 are so shaped as to form with the outside wall 40 a kind 20 of pocket or shoe each of which is disposed in an angle of approximately 45° towards the plane of the bottom of the basket shaped turbine wheel 23. The highest point of the wings 41 lies under such conditions approximately 25 in the middle of the height of the turbine wheel 23 and as this point offers the longest lever arm for the utilization of the water pressure, I provide an aperture 42 in the chamber 32 so that the connecting line 30 between the highest point of the wings 41 and said aperture 42 forms a right angle with the aforesaid central axis of the wings.

In order to avoid any lateral spreading of the jet of water and to concentrarte its full 35 power upon the wings, I mount a nozzle 43 having an aperture 42 and conduct thereby the water as closely as possible to the wings to hit the same with the full force on the inside at the highest point.

40 This relation brought about between the handle and the turbine wheel is important for various reasons; it allows on the one side the best mechanical recovery of the water power and on the other side because 45 it gives the handle a location in relation to the shell 10 which is the most convenient to the person using the machine in view of the anatomy of the hand. The machine can be comfortably held in the hand and can 50 be easily directed over the surface to be cleaned without causing the slightest feeling of fatigue. For using the machine for washing dishes or the like the rubber hose 35 is connected to the faucet furnishing the 55 hot and cold water; then I unscrew the plug 28 and insert through the opening of the sleeve 27 as many moderately sized pieces of hard soap as the space 44 between the shell 10 and plate 24 will hold; then I turn 60 on the hot water and the wiper 20 starts to rotate, being at the same time flushed with the water leaving through the apertures 13. As soon as the water runs, it fills also the space 44, dissolves the soap therein and 65 the soap solution is then continuously mixed

with the main part of the water flushing the wiper 20. As soon as the machine is held upon a dish, or the like, any grease, waste of food or the like dirt is easily removed. If a hard crust of carbon, adhering to the pans, is to be removed, the wiper 20 may be detached if too soft and may be exchanged for another one of harder material; if more costly and sensitive articles, such as silver ware, fine china or the like are 70 to be cleaned, even the softest wiper 20 may be dispensed with and the soap water alone will be sufficient to clean such goods. The vent hole 29 in the plug 28 admits air into 75 the space 44 and by agitating the water contributes materially to the dissolving of the soap in said space 44, for as soon as I close 80 said vent hole 29 the dissolving of the soap is so much reduced that the water still coming out of the machine carries so little soap that it can be disregarded and the water can be declared to be almost entirely free 85 of the same which is important for rinsing the cleaned dishes.

Another great convenience of my new washing machine is afforded by the gate valve 37 which owing to its spring actuated lever automatically shuts off the supply of water and automatically opens it again and brings the machine to action when I take 90 the handle into my hand because in doing so I press the lever 39 with the gate 37 attached thereto downwardly and open the way for the water.

Finally I wish to say that a wire netting 45 may be inserted in the cone shaped part of the shell 10; owing to the centrifugal force with which the turbine wheel 23 throws out the water, it leaves the apertures 13 with considerably more than the necessary force and for that reason the wire netting 45 is inserted to reduce the force of the water to the required degree.

The machine described above is the best example of my invention as I understand the invention at present and it is understood that many changes in the spaced relation between the shaft, the rotary members and the means supplying the water may be arranged without sacrificing the advantages of or deviating from the spirit of the invention and any such change comes within the appended claims.

What I claim is:

1. In a washing machine the combination comprising a hollow shell having a pointed end, a rotary shaft projecting from said shell at its pointed end, gearing means secured to said shaft, a bracket to serve as a journal for said rotary shaft, gearing means engaging the gearing on said rotary shaft, water actuated means driving said gearing means, a plate with an aperture dividing off a compartment within the shell, an entrance into said compartment, means to close said 120

125

130

entrance, means to supply water to the water actuated means, and a wiper detachably secured to the end of the shaft projecting from the shell.

5 2. In a washing machine the combination comprising a hollow shell having a pointed end, a rotary shaft projecting from said shell at its pointed end, gearing means secured to said shaft, a bracket adapted to 10 serve as a journal for said rotary shaft, gearing means engaging the gearing on said rotary shaft, water actuated means driving said gearing means, a plate with an aperture dividing off a compartment within the shell, 15 an entrance into said compartment, means to close said entrance, an air vent in said closing means, means to supply water to the water actuated means, and a wiper detachably secured to the end of the shaft project- 20 ing from the shell.

3. In a washing machine the combination comprising a hollow shell having a pointed end, a rotary shaft projecting from said shell at its pointed end, gearing means secured to 25 said shaft, a bracket adapted to serve as a journal for said rotary shaft, gearing means engaging the gearing on the rotary shaft, a turbine wheel driving said gearing means, a plate with an aperture dividing off a compartment, means to close said entrance, 30 means to supply water to the turbine wheel, and a wiper detachably secured to the end of the shaft projecting from the shell.

4. In a washing machine the combination comprising a hollow shell having a pointed end, a rotary shaft projecting from said shell at its pointed end, gearing means secured to said shaft, a bracket adapted to serve as a journal for said rotary shaft, 35 gearing means engaging the gearing on the rotary shaft, a turbine wheel driving the said gearing means, a plate with an aperture dividing off a compartment within the shell, an entrance into said compartment, means to 40 close said entrance, an air vent in said closing means, and a wiper detachably secured to the end of the shaft projecting from the shell.

5. In a washing machine the combination comprising a hollow shell having a pointed end, a rotary shaft projecting from said

shell at its pointed end, gearing means secured to said shaft, a bracket adapted to serve as a journal for said rotary shaft, gearing means engaging the gearing means on the rotary shaft, a turbine wheel driving said gearing means, a plate with an aperture dividing off a compartment within the shell, an entrance to said compartment, means to close said entrance, an air vent in said closing means, a wiper detachably secured to the end of the shaft projecting from the shell, and tubular means supplying water to the turbine wheel.

6. In a washing machine the combination comprising a hollow shell having a pointed end, a rotary shaft projecting from said shell at its pointed end, gearing means secured to said shaft, a bracket adapted to serve as a journal for said rotary shaft, gearing means 65 engaging the gearing on the rotary shaft, a turbine wheel driving the said gearing means, a plate with an aperture dividing off a compartment within the shell, an entrance into said compartment, means to close said entrance, an air vent in said closing means, 70 a wiper detachably secured to the end of the shaft, projecting from the shell, a tubular handle, and a gate valve operatively opening and closing said handle on seizing and re- 75 leasing, respectively, the same.

7. In a washing machine the combination comprising a hollow shell having a pointed end, a rotary shaft projecting from said shell at its pointed end, gearing means secured to said shaft, a bracket adapted to serve as a journal for said rotary shaft, gearing means engaging the gearing on the rotary shaft, a turbine wheel driving the said gearing means, a plate with an aperture di- 85 viding off a compartment within the shell, an entrance into said compartment, means to close said entrance, an air vent in said closing means, a wiper detachably secured to the end of the shaft projecting from the shell, 90 and a tubular handle supplying water to the inside of the wings of the said turbine wheel in a substantially right angle to said wing.

In witness whereof I have hereunto set my hand this 7th day of May, 1927.

OTHMAR MAYCEN.
